Primary Examiner — Marie D. Fast Horse*Assistant Examiner* — Josiah D. Parsons(74) Attorney, Agent, or Firm — Leanne Taveggia Farrell; Westman, Champlin & Koehler, P.A.(57) CLAIM

The ornamental design for a checkout station, as shown and described.

DESCRIPTION

FIG. 1 is a perspective view of a checkout station showing our new design;

FIG. 2 is a front view thereof;

FIG. 3 is a right side view thereof; and,

FIG. 4 is a top view.

The broken lines are included for purposes of illustrating portions of the checkout station that form no part of the claimed design.
